POWER DIVIDER CIRCUIT

Richard C. Raymond, State College, Pa.

Application September 14, 1945, Serial No. 616,403

8 Claims. (Cl. 333—7)

1

This invention relates to a radio frequency power divider circuit, and particularly to one where the power may be divided in any suitable proportion between two outputs without materially changing the combined impedances of these outputs as seen from the input.

It is therefore an object of this invention to provide a means for dividing in any suitable proportion the radio frequency power output to a pair of transmission lines.

It is another object of this invention to provide a means for dividing in any suitable proportion the radio frequency power output to a pair of transmission lines and having incorporated therewith a means for regulating said proportion at will.

It is another object of this invention to provide a transmission line construction having an input line, and a pair of output transmission lines joined thereto with a means for dividing in any suitable proportion the power output from each of said parallel output lines without materially disturbing the effective terminating impedance of said input line.

Other objects and features of the present invention will become apparent upon a careful consideration of the following detailed description when taken together with the accompanying drawing, where the figure illustrates an elevational view generally in cross section of a typical embodiment of the invention.

The input transmission line, shown at 75, is expanded in partial cross-section by the tapered portion 76 before connecting with the output transmission lines 77 and 78 at a stub-supported joint 79 at which the short-circuited stub transmission line 80 is adapted to act as an electrically resonant mechanical support in accordance with well-known principles. A metallic rod 82 is mounted coaxially with respect to the transmission lines 77 and 78, passing through a suitable aperture in the central conductor 83 of the transmission lines 75, 76, 80. In its central portion the shape of the rod 82, which is elsewhere cylindrical, is modified to provide a rack adapted to engage a pinion 85 mounted upon the shaft 86, so that the rod 82 may be longitudinally propelled either into the transmission line 77 and out of the transmission line 78 or vice versa, such propulsion being accomplished by turning of the shaft 86. The shaft 86 is provided with a gear wheel 87 which may engage a suitable motor drive.

Two generally cylindrical spring grip structures 88 and 89 are mounted on the conductor 83 in

2

order to preserve the alignment of the rod 82 and to provide firm electrical contacts between the rod 82 and the conductor 83. Let it be assumed that the transmission line 77 leads to one load and the transmission line 78 leads to another load. The structure 89 which extends towards the transmission line 77 should then be approximately a quarter-wave length long and the spring grip structure 88 which extends toward the transmission line 78 should be approximately a half-wave length long, dimensions given in terms of wave length having reference to electrical length. The central conductors 90 and 91 of the transmission lines 77 and 78 respectively are then so positioned that they come almost to the ends of the spring grip structures 88 and 89 respectively. The ends of the conductors 90 and 91 are hollowed out, preferably for substantially more than a half-wave length. When the rod 82 extends for a half-wave length into the hollowed end of the conductor 91, a transmission line is formed having the rod 82 and the conductor 91 as conductors and having an electrical length of a half-wave length. Since this transmission line is open-circuited at its left-hand end, because the hollow portion of the conductor 91 is considerably longer than a half-wave length, a high series impedance will be presented by the gap to the right of the end of the conductor 91, thus preventing power from proceeding down through the transmission line 78. Because this gap is located at approximately a half-wave length from the junction, the shunt impedance offered by the transmission line 78 at the junction will be high and will exert relatively little interference with transmission of power from the transmission line 75 into the transmission line 77.

The rod 82 is of such length that at the same time that it extends approximately a half-wave length into the hollow portion of the conductor 91, it extends approximately a quarter-wave length into the hollow portion of the conductor 90, thus providing a relatively low series impedance at the gap at the left-hand end of the conductor 90 and allowing power to be transmitted into the transmission line 77 with practically no obstruction. As the rod 82 is gradually moved to the right, a gradually increasing capacitive series impedance will be presented at the gap to the left of the conductor 90, while a gradually decreasing capacitive series impedance will be presented at the gap to the right of the end of the conductor 91. The shunt impedance of the transmission line 77, as seen at the approximate location of the gap at the left end of the con-

What is claimed is:

5 ductor 90, will thus be capacitive, and as seen from the junction the shunt impedance will then be inductive, because of the intervening quarter-wave length of line. The shunt impedance as seen from the junction of the transmission line 78 will be capacitive because the gap at the right-hand end of the conductor 91 is located at a half-wave length from the junction. There will thus be some compensation between the reactive components of the shunt impedances, reducing the 10 standing waves in the transmission line 75. This compensation is not complete, and becomes less complete as the rod 82 is moved to the right, for finally, when the rod 82 is inserted in the hollow 15 part of the conductor 90 to the extent of a half-wave length, a high impedance is presented at the gap to the left of the end of the conductor 90, which causes a short circuit to appear at the junction. This type of device is therefore useful only for a limited range of variation of the power 20 transmission to the transmission line 77 in the neighborhood of full transmission thereto, because when it is desired to transmit a relatively large proportion of power to the absorber through the transmission line 78, there will be a tendency 25 for substantial standing waves to build up in the transmission line 75.

If the end of the conductor 90 were brought to a point about a half-wave length from the junction instead of to a point about a quarter-wave length from the junction, and the rod 82 were accordingly lengthened by a quarter-wave length, there would be no substantial mismatch of the line 75 at either extreme position of the rod 82, but the reactive component of the shunt impedance of the transmission lines 77 and 78 as seen from the junction would both have the same sign so that a mismatch would occur for intermediate positions of the rod 82. For the purpose of this invention, therefore, the arrangement shown in 40 the figure is better than that just mentioned.

If desired the end of conductor 90 may be brought to a point about a half-wave length from the junction instead of to a point about a quarter-wave length as disclosed above, and rod 82 may be likewise lengthened by a quarter wavelength at the end adjacent conductor 90. There will now be no substantial mismatch of line 75 at either extreme position of rod 82, but the reactive component of the shunt impedance of transmission lines 77 and 78 as seen from the junction would both have the same sign so that a mismatch would occur for intermediate positions of rod 82.

It is to be understood in connection with the power divider apparatus that whenever electrical lengths of a quarter or half wave length are specified, an odd multiple or even multiple, respectively, of a quarter wave length may be used equally as well. Likewise, where the term electrical length is used, it is to be understood as meaning a physical length of such value as to give the electrical effect of the corresponding electrical length in free space. Thus, the electrical lengths mentioned are to be taken as including the contribution of "end effects." All distances referred to in terms of wave lengths are intended to be taken as electrical lengths as defined above.

Although I have shown and described only certain specific embodiments of the invention, I am fully aware of the many modifications possible thereof. Therefore, this invention is not to be limited except insofar as is necessitated by the prior art and the spirit of the appended claims.

1. A radio frequency power divider circuit, comprising an input coaxial transmission line having inner and outer conductors and being short circuited at one end thereof, a pair of coaxial output transmission lines also having inner and outer conductors, said outer conductors being joined to said input line at diametrically opposite points and at a distance of any odd multiple of a quarter wave length from said short circuited end, the mutually directed ends of said inner conductors of said output lines being hollowed out for a length greater than one-half wave length, the difference in spacing of said ends from the inner conductor of said input line being an integral number of quarter wave lengths, a rod electrically joined to the inner conductor of said input line coaxially aligned with the inner conductors of said output lines and extending a predetermined distance into the hollowed portion of said inner conductors of said output lines.

2. A radio frequency power divider circuit, comprising an input coaxial transmission line having inner and outer conductors and being short circuited at one end thereof, a pair of coaxial output transmission lines also having inner and outer conductors, said outer conductors being joined to said input line at diametrically opposite points and at a distance of any odd multiple of a quarter wave length from said short circuited end, the mutually directed ends of said inner conductors of said output lines being hollowed out for a length greater than one-half wave length, a rod electrically joined to the inner conductor of said input line coaxially aligned with the inner conductors of said output lines and extending a predetermined distance into the hollowed portion of said inner conductors of said output lines, and means for varying the axial portion of said rod encompassed by each of said hollowed portions.

3. A radio frequency power divider circuit, comprising an input coaxial transmission line having inner and outer conductors and being short circuited at one end thereof, a pair of coaxial output transmission lines also having inner and outer conductors, said outer conductors being joined to said input line at diametrically opposite points and at a distance of any odd multiple of a quarter wave length from said short circuited end, the mutually directed ends of said inner conductors of said output lines being hollowed out for a length greater than one-half wave length, a rod electrically joined to the inner conductor of said input line coaxially aligned with the inner conductors of said output lines and extending a predetermined distance into the hollowed portion of said inner conductors of said output lines, and a rack provided at the central portion of said rod and a driving means associated with said rack for varying the axial portion of said rod encompassed by each of said hollowed portions.

4. A radio frequency power divider circuit, comprising an input coaxial transmission line having inner and outer conductors and being short circuited at one end thereof, a pair of coaxial output transmission lines also having inner and outer conductors, the outer conductors of said output lines being joined to the outer conductor of said input line at diametrically opposite points and at a distance of any odd multiple of quarter wave lengths from said short circuited end, the mutually directed ends of the inner conductor of said output lines being spaced substantially a distance of a quarter and a half wave length, re-

spectively, from the inner conductor of said input line and being hollowed out for a length substantially greater than a half wave length, a rod electrically joined to the inner conductor of said input line and extending into the hollowed end of said inner conductor spaced a half wave length for a distance of a half wave length and extending into the hollowed end of said conductor spaced a quarter wave length for a distance of a quarter wave length, a rack provided on the central portion of said rod, and a pinion rotatable by a shaft and connected to said rack for varying the axial position of said rod with respect to said hollowed ends, whereby the input power may be proportioned between the output transmission lines in accordance with the rotation of said shaft.

5. A radio frequency power divider comprising, an input coaxial line and two mutually directed output coaxial lines, each of said lines having relatively stationary inner and outer conductors, said outer conductors being joined to form a hollow T, the inner conductor of said input line penetrating to the junction of said hollow T, each of the inner conductors of said output lines also penetrating said T but being spaced from said junction, and a rod movable along the common axis of said output lines, said movable rod being in electrical contact with said inner conductor of said input line and in spaced, variable capacitive relationship with both of the inner conductors of said output lines.

6. A radio frequency power divider circuit, comprising an input coaxial transmission line having inner and outer conductors and being short-circuited at one end thereof, a pair of coaxial output transmission lines also having inner and outer conductors, the outer conductors of said output lines being joined to the outer conductor of said input line at diametrically opposite points and at a distance of an odd multiple of quarter wave lengths from said short-circuited end, the mutually directed ends of the inner conductors of said output lines being spaced substantially a distance of a quarter, and of a half wave length, respectively, from the inner conductor of said input line, means electrically connected to said inner conductor of said input line and capacitively coupled to said inner conductors of said output lines, and means for varying the position of said first-mentioned means to simultaneously vary the capacitive coupling between

said first-mentioned means and said inner conductors of said output lines.

7. A radio frequency power divider comprising, an input coaxial line and two mutually directed output coaxial lines, each of said lines having an inner and an outer conductor, said outer conductors being joined to form a hollow T, the inner conductor of said input line penetrating to the junction of said hollow T, each of the inner conductors of said output lines also penetrating said T but being spaced from said junction by multiples of a quarter wave length, the mutually aligned ends of the inner conductors of said output lines being hollowed out for a distance greater than a half wave length, a movable rod disposed partially within said hollowed out ends of said inner conductors of said output lines in noncontacting relationship therewith, said movable rod having a length greater than the spacing between said mutually directed ends by an odd multiple of quarter wave lengths greater than one quarter wave length, and means conductively coupling said movable rod to the inner conductor of said input line, said movable rod being movable axially of itself thereby to vary the coupling between said input coaxial line and said output coaxial lines.

8. A power divider as in claim 7 wherein said means conductively coupling said movable rod to said inner conductor of said input line comprises, first and second stub inner conductors rigidly secured to said inner conductor of said input line and extending to points adjacent the mutually directed ends of the inner conductors of said output lines, said movable rod being slidably journaled within said stub inner conductors.
